INDICATOR HOUSING

Samuel J. Koch, 26 Martin Court, Great Neck, N.Y.

Filed Aug. 18, 1960, Ser. No. 61,807

Term of patent 14 years

(Cl. D26—13)

FIG. 3

FIG. 2

FIG. 1

Fig. 1 is a front view of an indicator housing, showing my new design.

Fig. 2 is a side view thereof.

Fig. 3 is a top view thereof.

Fig. 4 is a rear view thereof.

I claim:

The ornamental design for an indicator housing, substantially as shown.
